6 Claims**ABSTRACT OF THE DISCLOSURE**

A reciprocating lapping machine for railroad car air brakes, having one or more stations each provided with parallelly extending spaced apart work supporting rods between which an abrasive or lapping carrying member is reciprocated in parallel relation with respect to the rods in lapping engagement with the work.

Our invention relates to a reciprocating lapping machine for railroad car air brakes and has for its principal object the provision of an arrangement for lapping the valve seat of an air brake housing in a highly efficient and effective manner.

Among the several objects of the invention is the provision for lapping the valve seats of a plurality of air brake housings simultaneously.

Another and equally important object of the invention is the provision for supporting the air brake housing in an effective and simple manner during the lapping of the slide valve seat thereof.

Other objects will appear hereinafter.

The invention consists in the novel combination and arrangement of parts to be hereinafter described and claimed.

The invention will be best understood by reference to the accompanying drawings showing the preferred form of construction, and in which:

FIG. 1 is a perspective view of the lapping machine embodying our invention;

FIG. 2 is a horizontal sectional detail view of the same;

FIG. 3 is a fragmentary perspective view showing an air brake housing in lapping position;

FIG. 4 is a fragmentary sectional detail view taken substantially on line 4—4 of FIG. 2;

FIG. 5 is a perspective view of a lapping block embodied in the invention.

The several objects of our invention may be accomplished by the preferred form of construction shown in the accompanying drawings and in which there is provided an enclosure or housing 10 having end walls 11, a front wall 12, a back wall 13 to which a cover 14 is hingedly connected.

The front wall 12 has a plurality of openings 15 formed therein in equal spaced relation with respect to each other. Mounted on the bottom wall 16 of the housing adjacent the opposite ends 11 thereof, are mounting blocks 17 arranged in pairs and each pair supporting a rod 18. The rods 18 are held in fixed position with respect to the blocks 17 by set screws 19.

Mounted for reciprocation upon the rods 18 are blocks 20 which are connected to and support a ram bar 21. The bar 21 is fixed to the blocks 20 as at 22. Formed in the ram bar 21 are a plurality of equally spaced openings 23. Projected through each of the openings 15 from the interior of the housing 10 is a lapping arm 24. The interior end of this lapping arm 24 is reduced and mounted in a slot formed in a yoke 25 and fixed thereto by means of a pin 26. The yoke 25 has a reduced portion 27 which projects into the openings 23. Threaded

2

into this reduced portion 27 is a threaded bolt 28 by means of which the yoke 25 is fixedly secured to the bar 21.

Adjacent each of the openings 23 there is formed in the ram bar 21 an opening 29 having a threaded plug 30 threaded therein against a spring 31, the inner end of which bears against the arm 24.

The outer end portion of the arm 24 carries a head bearing pin 32 which is adapted to fit in a socket 33 of a lapping block 34 formed of such material as will effectively serve for lapping purposes. Such arrangement permits self alignment of the lapping block 34 while in motion, thus eliminating critical alignment of the air brake housing on the machine.

Carried by the front wall 12 in spaced relation with respect to each other and in pairs, are a plurality of work-supporting shafts 35, the pair of shafts being arranged on opposite sides of a lapping arm 24 and in a predetermined relation with respect thereto as may be required by the workpiece to be lapped. Fixed upon each shaft 35 are a pair of fixed clamps 36 and 37 which, as hereinafter explained, serve to hold the air brake housing in position during the lapping operation.

The ram bar 21, together with the arms 24 supported thereby, is adapted to reciprocate in a horizontal plane. For this purpose, any suitable means may be employed for effecting the reciprocation of the ram bar 21 and the arms 24. For purposes of illustration, we have shown an air cylinder 38 which may be of any improved construction, including a plunger 39 which is fixed to the ram bar 21 as at 40. This cylinder has air supply conduits 41 through which air is admitted to the cylinder 38 for the intended purpose.

In FIG. 3, we have illustrated an air brake housing 42 mounted in position on an adjacent pair of shafts 35 with the lapping arm 24 projecting therethrough. The shafts 35 project through ports 42' formed in the workpiece. In such position the lapping block 34 will ride in a valve seat 43 as shown in FIG. 3. The clamps 36-37 are of the split type, wedged together by means of suitable set screws 35'. When the housing 42 is mounted upon adjacent shafts 35, the outer clamps 37 are pressed against the housing to bear the same against the inner clamps 36, at which time the clamps are tightened upon the shafts 35 by the set screws 35'.

By this arrangement the housing 42 is firmly held in position with the lapping block 34 engaging the valve seat 43 for reciprocation therein to perform the lapping operation.

The lapping block 34 is yieldably held in lapping position within the valve seat 43 by the spring 31. By adjustably threading the plug 30 against the spring 31, the amount of yieldable pressure exerted on the lapping arm 24 may be controlled.

When certain of the arms 24 are ineffective by reason of the fact that the adjacent shaft 35 do not support thereon workpieces, to prevent the arms 24 from rubbing against the wall 12, they are supported free of the wall 12 by means of adjustable fiber washers 44 (as seen in FIG. 4) the washer 44 being eccentrically connected as at 25 to the wall 12. The position of the shafts 35 on opposite sides of the arm 24 may be relocated by positioning such shafts in openings 46 provided in the front wall 12, as seen in FIG. 1.

From the foregoing it is apparent that we have provided an effective machine for lapping the slide valve seat of an air brake housing, the machine being constructed so as to handle one or more of such housings during a single operation. There are relatively few parts involved in the construction, which affords manufacture at an economical cost.

While we have illustrated and described the preferred form of construction for carrying our invention into effect, this is capable of variation and modification without departing from the spirit of the invention. We therefore do not wish to be limited to the precise details of construction set forth, but desire to avail ourselves of such variations and modifications as come within the scope of the appended claims.

Having thus described our invention, what we claim as new and desire to protect by Letters Patent is:

1. A lapping machine of the class described comprising
  - (a) a plurality of lapping stations,
  - (b) each station comprising a pair of work-supporting shafts extending in parallel relation with respect to each other,
  - (c) means for removably clamping a workpiece to said shafts,
  - (d) a lapping bar extending approximately parallel to said shafts and having a reciprocal lapping element carried adjacent the outer end of said lapping bar in lapping engagement with said workpiece,
  - (e) means for reciprocating said lapping bar relative to the shafts.
2. A lapping machine of the class described comprising
  - (a) a reciprocatory ram bar,
  - (b) means for supporting said bar for reciprocation,
  - (c) a plurality of arms carried by and extending from said bar in substantial parallel relation with respect to each other and simultaneously reciprocated with said bar,
  - (d) a lapping element carried by each of said arms adjacent the outer end thereof,
  - (e) means disposed on opposite sides of each of said arms in approximate parallel relation with respect to each other for supporting a workpiece having a slide valve seat,
  - (f) said lapping element being adapted to lappingly

engage said seat during reciprocation of said arms by said bar.

5 3. The lapping machine defined by claim 2 wherein the means for supporting the ram bar comprises a pair of reciprocating blocks, a supporting shaft for each block, and standards supporting said shaft.

10 4. The lapping machine defined by claim 2 wherein the lapping element comprises a lapping block having a socket formed therein and a head-bearing pin carried by each of said arms and projecting into said socket to permit the block to self-adjust itself relative to the surface of said valve seat.

15 5. The lapping machine defined by claim 3 wherein the lapping element comprises a lapping block having a socket formed therein and a head-bearing pin carried by each of said arms and projecting into said socket to permit the block to self-adjust itself relative to the surface of said valve seat.

20 6. The lapping machine defined in claim 2 characterized by the inclusion of spring means acting on said arms to yieldably urge the lapping element into lapping engagement with said valve seat.
